UNITED STATES PATENT OFFICE.

LUDWIG J. SWOBODA, OF MINNEAPOLIS, MINNESOTA.

FEEDER.

SPECIFICATION forming part of Letters Patent No. 451,532, dated May 5, 1891.

Application filed August 30, 1890. Serial No. 363,545. (No model.)

To all whom it may concern:

Be it known that I, LUDWIG J. SWOBODA, of Minneapolis, in the county of Hennepin and State of Minnesota, have invented certain Improvements in Feeders, of which the following is a specification.

My invention relates to automatic feeders of the class in which a constantly-rotated feed-roller or a constantly-vibrated feed-board is used in the outlet-opening of the feed-hopper, the office of the same being to carry the material steadily from the hopper and to spread the same into a thin stream as it leaves the hopper and falls between the rolls or upon the sieves of the machine in connection with which the automatic feeder is employed. The stock or material is fed into the feed-hopper above the feed roll or board from a suitable spout connected in turn with the elevator or other conveyer, which conveyer is in its turn connected with other parts of the milling machinery. It has been found that the feed through the spout into the feed-hopper will vary so that at times the roll or board operating at a constant speed and in connection with an opening of a given size will fail to carry off the material as fast as it is fed into the hopper, the result being that the feed hopper and spout will be choked with material and the elevator or conveyer stopped by the over-plus material, thus causing an annoying and damaging delay, and sometimes necessitating the shutting down of the mill. At other times very little material will come through the spout into the hopper, and there will not be enough material to spread across the outlet-opening, the consequence being that only portions of the feed-roll will be covered with material, and the material will be fed into the rolls or other part of the machine in uneven quantities or lumps, thus damaging and cutting down the efficiency of the machine to which the feeder is attached and producing a poor and uneven quality of flour or other finished stock. In order to avoid these detrimental results, various forms of feed-controlling gates have been designed, the same being adjusted either by hand or automatically to increase or decrease the size of the outlet-opening above the feed roll or board as the quantity of material contained in the

feed-hopper varies from the normal. Much difficulty has been experienced in so constructing these gates and their regulating apparatus as to insure their reliability, for if the action of the feed-gate be slow or inaccurate the same difficulties will be encountered as in the use of the feeder without the feed-controlling gate.

In one class of automatic feeders the raising and lowering of the feed-gate has been accomplished through the medium of a suitable bridge or pressure-board provided within the feed-hopper and connected with the feed-gate by suitable link-and-spring connections. These spring connections tend to constantly hold the spring-gate at the normal height above the roller and are under constant tension. As the pressure of the material upon the bridge-board increases the board will be forced down a short distance, the tension of the springs overcome, and the feed-gate raised to allow a thicker stream of material to pass out over the feed-roll, thus emptying the hopper fast enough to prevent choking. In case only a small weight of material is allowed to fall into the hopper and upon the pressure or bridge board, the latter will be raised by the tension of the springs and the feed-gate lowered to approach or close upon the feed-roll or vibrating board, thereby lessening the size of the outlet-opening and always confining enough of the material within the hopper to cover the bottom thereof and spread clear across the feed-roll, thus insuring an even feed.

In practice it has been found that these feeders, the operation of which is dependent upon coiled or other springs, soon become unreliable, slow of action, and easily deranged on account of changes in the strength of the various springs and friction of parts. In order to overcome the various objections to feeders heretofore constructed, I have designed an automatic feeder in which reliance upon springs under constant tension is dispensed with and balance and construction of parts depended upon for the operation of the feed-gate.

My invention consists in the combination, with the feed-hopper provided with the usual outlet-opening and feed-roll or feed-board, of a straight feed-gate adapted to close said

opening, long pivot-arms on said feed-gate projecting out therefrom and pivoted, preferably, at points lying in a plane at right angles to the inner face of the feed-gate, a slotted bracket or brackets extending back from the top of the feed-gate, a pressure board or bridge provided within the said hopper, said board hinged along its upper edge to the side of the hopper having the outlet-opening, an arm provided on said bridge-board and extending from the upper edge thereof through the side of the hopper and overhanging said slotted bracket, and a longitudinally-adjustable pivotal link extending between said slotted bracket and said arm provided on the bridge-board, and a flexible cloth extending on three sides of said bridge-board and closing in the space lying beneath the same between the bridge-board and the side of the hopper; and, further, my invention consists in a feeder having an auxiliary spring or springs in connection with the feed-gate, the tension of said spring or springs being readily adjustable, and the purpose of the same being to prevent the vibration of the feed-gate, which would otherwise be caused by the vibration of the machine to which the automatic feeder is attached.

My invention consists, further, in various details of construction, hereinafter described, and particularly pointed out in the claims.

My invention will be more readily understood by reference to the accompanying drawings, in which—

35 Figure 1 is a transverse section of a feed-hopper provided with an automatic feeder embodying my invention, the section being taken upon line *xx* of Fig. 2. Fig. 2 is a partial front elevation thereof. Fig. 3 is a 40 detail plan view of the slotted horizontal bracket used upon the feed-gate. Fig. 4 is a sectional elevation thereof upon the line *yy* of Fig. 3. Fig. 5 is a partial side elevation of my automatic feeder as used without the 45 auxiliary spring. Fig. 6 is a detail plan view of the slotted bracket adapted to confine the upper end of the auxiliary-spring rod. Fig. 7 is a section thereof upon the line *zz* of Fig. 5. Fig. 8 is an elevation showing the bridge-board and the deflector-plate or divider thereon, as seen from the line *ww* of Fig. 1.

As shown in the drawings, the feed-hopper 2, having the slanting sides 3 and 4, is provided with the wide opening 5 between the 55 lower edge of the side 4 and the feed-roll 6. This feed-roll is rotated at a constant high speed in the direction of the arrow and serves to carry the material out of the bottom of the feed-hopper and drop it upon the rolls or 60 the sieve of the machine. The feed-gate 7 serves to normally close the wide opening 5, and when the feeder is not in use rests upon the feed-roll 6. This long feed-gate 7 is preferably made of wood, and is strengthened by 65 the metal strip 8 upon its lower edge, which both makes the gate more durable and gives it the requisite weight. Connected with this

gate is my automatic feed apparatus, which in its action may be likened to a pair of scales, the parts thereof being adjustably balanced 70 one with the other, so that the gate is raised to a certain distance when a certain weight of material has been placed in the hopper.

For general use in connection with machines having vibratory parts and motions I 75 make use of the apparatus shown in Fig. 1, while the form embodied in Fig. 5 is generally used with machines which run quietly and smoothly without vibration, the auxiliary spring being dispensed with as unnecessary 80 for use in connection with such machines.

The feed-gate 7 is provided at each end with arms 9, suitably pivoted at their lower ends, as shown, to stationary bearings secured upon the sides of the machine or the 85 feeder-box. The relation of the feed-gates 7, the arms 9, and the pivot-points thereof is such that the pivot-points lie in a plane projected at an angle of ninety degrees with the inner face of the feed-gate. By this construction I bring the pivot-points below the edge of the feed-gate and do away with the necessity of curving the inner surface of the feed-gate 90 7, and still make the connection between the gate and the side 4 close enough to prevent 95 spilling out of the material. Within the feed-hopper I provide the hinged or pivoted pressure or bridge board 10, hinged along its upper edge 11. This board is prevented from rising too high in the hopper by suitable 100 flexible retaining sides 12, preferably made of cloth and adapted to fold beneath the board when the same is forced down by the pressure of the grain above it. This cloth extends on three sides of the bridge-board, 105 closing the space beneath the same and preventing the material from passing under the board to hinder its downward movement. A suitable divider or deflecting-plate 13, having the form shown, is preferably provided upon 110 the upper surface of this bridge-board and extends clear across the same, so that the material which falls from a central point above the feed-hopper will be spread clear across the bottom of the hopper. The movement of 115 the bridge-board 10 as it rises and falls according to the pressure of material upon it is communicated to the feed-gate to raise or lower the same by the adjustable pivotal link 14, the arm 15, secured to the board 10 and 120 operating through the slot 16 in the side 4, and the horizontal slotted bracket 17, extending from the top of the feed-gate 7. The link 14 is provided with suitable eyes 18, of the form shown in Figs. 3 and 4. The lower end or 125 eye of the link engages with the notched lug 19, extending from the locking-block 20, adjustably fixed upon the slotted bracket 17 by 130 the bolt and nut 21 passing through the slot 22 in said bracket 17. The upper eye of the link 14 is pivoted at 23, and is made adjustable upon the arm 15 by the movable sleeve or block 24, adapted to be locked upon said arm by the set-screw 25. The link 14 is easily

adjusted by means of the threaded link 26 engaging the right and left hand screws upon the adjacent ends of the link 14. In order to prevent the raising of the feed-gate to too great a height, I provide the stop 27, adapted to be raised or lowered by simply turning the bolt 28. This bolt 28 is secured in the bracket 29 upon the side 4 by the short pin 30, provided in the bolt 28 to prevent its being pushed up through the bracket when the stop 27 is struck.

Thus far I have described the simple form embodied in Fig. 5, which is all that is necessary for quiet machines, such as roller-mills. In case, however, that the feeder is to be used upon a purifier or other machine having vibrating parts, I preferably employ the rod 31, provided with the sharp point at its lower end adapted to rest in a suitable socket provided in the head of the movable bolt 32, secured in the slot 33 of the bracket 17. The upper end of this rod 31 is free to move up or down through a suitable opening 34, provided in the adjustable block 35. This block 35 is adapted to be held always at right angles to the slotted bracket 36, but may be moved in or out toward the end of the slot therein by simply loosening the bolt 37. The spiral spring 38 is provided upon the rod 31 and is adapted to be adjusted by means of the thumb-screw 39, provided upon the threaded portion of the same, as shown. The tension of this spring, though very slight, is just enough to prevent the vertical vibration of the feed-gate 7, which would otherwise result from the general vibration of the machine and cause an unsteady feed. The tension of the spring 32 is so slight that the increase therein when the feed-gate is raised a short distance practically amounts to nothing, and therefore does not affect the operation of the feed-gate as controlled by the fluctuations of the bridge-board 10.

The operation of my feeder is very simple and has proved to be thoroughly automatic and reliable. The normal position of the feed-gate may be determined with any weight of material which it is desired to feed by a short trial of the same and by moving the pivot-points of the link 14 in or out upon the arm 15 and the bracket 17; and, further, the position of the feed-gate may be adjusted very delicately after the positions of the ends of the links have been determined by simply turning the threaded link 26 to lengthen or shorten the link, thereby raising or lowering the gate, as desired. It will be seen that the leverages may be varied to almost any degree by the shifting of the locking-blocks at the pivot-points. Thus, for instance, if the upper pivot should be thrown out to the end of the arm 15 it would take a much greater weight of material upon the board 10 to raise the feed-gate by turning the same upon its pivots. The same is true when the lower end of the link 14 is moved out nearer the end of the bracket 17. If the ends of the link 14 were moved in to-

ward the side 4, the opposite would be true. When a heavier or a lighter class of material than that the hopper previously ran through is fed into the same and a change is made in the positions of the pivot-points, the feed-gate may be kept at the same distance above the feed-roll by lengthening or shortening the link, as described. A change in the tension of the spring 38 is made by moving the blocks 32 and 35 in or out upon their supports, and is finally and accurately adjusted by means of the thumb-nut 39 on the rod 31. It will be seen that the bridge-board pivoted at its upper edge and connected with the feed-gate pivoted upon the long arms 9 form a sensitive and comparatively delicate mechanism, though having all the strength and wearing qualities necessary in such a device. A very small quantity of material falling upon the divider 13 will be spread evenly into the bottom of the hopper and clear across the opening 5, and, striking upon the outer edge or part of the bridge-board 10, has a long leverage, and will consequently press the same down in proportion to its weight, thus raising the feed-gate sufficiently to allow just the right amount of material to pass out under the same. If, on the other hand, a large quantity of material is fed suddenly into the hopper and upon the bridge-board, the bridge-board will be quickly thrown down and the feed-gate immediately raised against the stop or limit 27, thus allowing a heavy but always even stream of material to pass over the roller 6. As the pressure of the material upon the feed-board decreases the feed-gate will be gradually lowered, thus always retaining enough material in the hopper to spread clear across the discharge-opening. This will be true even when the supply of material is cut off and the hopper allowed to empty itself. As the last part of the material passes out over the roll the feed-gate will settle down so near the roller and so evenly parallel with the same that though the stream be very light it will still be even. Having thus described my invention, I claim as new and desire to secure by Letters Patent—

1. The combination, with the feed-hopper having the outlet-opening, of a straight feed-gate, pivot-arms provided in connection with said feed-gate, pivots therefor, a bracket on said feed-gate extending outwardly therefrom, a bridge or pressure board provided within said hopper and pivoted along its upper edge to the side of the hopper having the said outlet-opening, a flexible cloth arranged around the sides and free edge of said bridge-board and closing in the space between the under side of the bridge-board and the said sides of the hopper, an arm provided in connection with said bridge-board extending therefrom through the side of the hopper, and a longitudinally-adjustable and pivotal link extending between said bracket and said arm, the ends of the link being movably secured

thereto and adapted to be moved in or out thereon, substantially as described.

2. The combination, in a feeder, of the feed-gate with the pressure board or bridge pivoted at its upper edge and adapted to yield downwardly to pressure exerted upon its top, a flexible cloth adapted to close the immediate space beneath said board or bridge, pivot-arms extending from said feed-gate at right angles thereto and secured at their outer ends upon suitable pivots, a slotted bracket provided on said feed-gate extending from the upper edge thereof, an arm provided on said bridge-board extending from the upper edge thereof, said bracket and said arm normally lying in substantially horizontal planes, and an adjustable link extending between and pivotally secured to said arm and bracket, the ends of said link being movable in or out thereon, substantially as and for the purpose specified.

3. The combination, with the feed-hopper provided with the opening 5, of the feed-gate 7, adapted to normally close said opening, the pivoted arms 9, pivoted in a plane at right angles to the inner face of said feed-gate, the bracket 17, provided with the slot adapted to engage the bolt of the locking-block 21, the feed-board 10, provided with the divider 13 and pivoted at its upper edge, the arm 15, projecting therefrom through a suitable slot in the side 4 of the hopper, the link 14, pivotally connecting said arm and said bracket, said link 14 being provided with the threaded link 26, adapted to engage the right and left threads upon the adjacent ends of the link 14, and the stop 27, adjustably secured upon the side 4 of the hopper.

4. The combination, in an automatic feeder, of the feed-hopper provided with the opening 5 with the feed-gate adapted to swing upon the pivoted arms 9, the bracket 17 upon said feed-gate, the bridge-board provided within said hopper and hinged at its upper edge, the arm extending outwardly from said upper edge of said bridge-board, the longitudinally-adjustable pivotal link adapted to connect said arm and said bracket and the upper and lower ends thereof adapted to be moved in or out and to be fixed in position upon the said arm and

bracket, and the adjustable stop secured upon the side of the hopper and adapted to limit the upward movement of said feed-gate, substantially as described.

5. The combination, in an automatic feeder, of the feed-hopper having the outlet-opening 5 with the feed-gate 7, the arms 9, provided on the feed-gate 7, the stationary pivots upon which said arms and gate are adapted to swing, the slotted bracket 17, the adjustable stop 27, secured upon the side of the hopper and adapted to limit the upward movement of said feed-gate, the bridge-board 10, provided with the divider 13 and hinged at its upper edge upon the side of the hopper, the arm 15, projecting through the slot 16 in the side 4, the adjustable link 14, pivoted upon the blocks 20 and 24, movably secured to the said bracket and the said arm, respectively, the rod 31, adapted to rest at its lower end in a suitable bearing 22, adjustably secured in a slot 33 of the bracket 17, the upper block 35, movably secured in the bracket 36, extending from the side 4 of the hopper, said block adapted to hold said rod against lateral movement, the spring 38 upon said rod 31, and the threaded thumb-nut 39, engaging therewith, substantially as described.

6. The combination, with the hopper provided with a suitable outlet-opening 5, of the feed-gate 7, adapted to close the same, the bracket 17, extending from and secured to said feed-gate, the bracket 36, secured upon the side of the hopper above said feed-gate, the rod 31, the lower bearing 32 for said rod, 85 and the upper retaining-block 35 of said rod, movably secured upon said upper bracket 36, the coiled spring 38 upon said rod, the threaded portion of said rod, and the thumb-nut 39 upon the same, by means of which the tension of said spring is increased or decreased, whereby vertical vibration of said feed-gate is prevented, substantially as described.

In testimony whereof I have hereunto set my hand.
